UNITED STATES PATENT OFFICE.

GERARD W. S. LEIJEN, OF MIDDLETOWN, PENNSYLVANIA.

DESIGN FOR A CHAIR.

6,367.

Specification for Design.

Patented Oct. 5, 1920.

Application filed April 26, 1920. Serial No. 376,885. Term of patent 14 years.

To all whom it may concern:

Be it known that I, GERARD W. S. LEIJEN, a citizen of the United States, residing at Middletown, in the county of Dauphin and State of Pennsylvania, have invented a new, original, and ornamental Design for a Chair, of which the following is a specification, reference being had to the accompanying drawings, forming a part thereof.

The figure is a perspective view of the chair showing my new design.

I claim:

The ornamental design for a chair as shown.

GERARD W. S. LEIJEN.
